2 SHEETS—SHEET 2.

UNITED STATES PATENT OFFICE.

FRED V. WILLIS, OF OSWEGO, ILLINOIS.

LIQUID-ELEVATING APPARATUS.

1,345,725.

Specification of Letters Patent.

Patented July 6, 1920.

Application filed January 2, 1920. Serial No. 348,726.

To all whom it may concern:

Be it known that I, FRED V. WILLIS, a citizen of the United States, residing at Oswego, in the county of Kendall and State 5 of Illinois, have invented a new and useful Improvement in Liquid-Elevating Apparatus, of which the following is a specification.

My invention relates to improvements in 10 liquid-elevating apparatus, more particularly, though not exclusively, for the lifting of water and of the type involving the use of a chamber adapted to receive the liquid to be elevated, in one of the cycles of the operation, compressed air being then introduced into the chamber to force the liquid therein out of the chamber, in the other cycle of operation, these operations continuing in alternation as the pumping continues.

20 My object, generally stated, is to simplify and render better adapted for use, apparatus of this type as hitherto provided, and render the same positive in operation and capable of continuous action with the minimum danger of impairment.

Referring to the accompanying drawings, Figure 1 is a view in elevation of apparatus constructed in accordance with my invention, showing the same as located in a well 30 the walls of which are shown in section. Fig. 2 is a broken, enlarged, vertical sectional view of the lower portion of the apparatus. Fig. 3 is a similar view of a detail of a valve employed. Fig. 4 is an enlarged view in elevation, partly sectional, of the portion of the apparatus shown as above ground in Fig. 1, the valve device therein shown being in the position it occupies during the supplying of air-pressure to the lifting cylinder.

Fig. 5 is a vertical elevational view of the apparatus of Fig. 4, but viewed at a 90° angle thereto, showing certain of the parts in section, this figure being viewed from the right in Fig. 4.

Fig. 6 is a similar view of the valve-mechanism referred to showing it in the position it occupies during the operation of the refilling of the lifting cylinder with the 50 liquid to be lifted.

In the preferred embodiment of my invention, I employ a cylinder 7 which is located in the receptacle from which the fluid, as for example, water, is to be lifted, the cylinder 7 being shown as supported at a foot 8 on the bottom of a well repre-

sented at 9, from which the water is to be lifted, the water level being represented at 10. The lower end of this cylinder contains a water inlet 11 with which co-operates a valve 12 formed of a valve stem 13 vertically movable in a bearing 14 in the foot 8 and a valve proper 15 secured to the upper end of the stem 13 and normally closing the inlet 11. The upper end of the cylinder is provided with a cap 16 through which a pipe 17 downwardly extends, this pipe being open at its lower end and terminating, preferably, a slight distance from the bottom of the cylinder. The pipe 17 extends upwardly to a casing 18 with which it is connected as shown, this casing containing an outwardly-opening valve shown as a ball 19 co-operating with a seat 20, the upper end of the casing 18 being connected with the pipe 21 through which the water is discharged to the desired point. The cap 16 contains a passage 22 opening into the cylinder 7 and connected at its upper end with a pipe 23 which extends upwardly, with a valve device 24 interposed therein of the construction, and for the purpose hereinafter described, the upper end of the pipe 23 opening into a coupling 31 with one end of which a valve device represented at 100 connects.

The valve device 100 comprises a valve-casing 25 in the form of a cylinder containing a valve proper formed of a stem 26 provided at its opposite ends with heads 27 and 28 fixed on this stem and sliding therewith in the cylinder 25, the cylinder 25 opening into the coupling 31 through a port 30 located above the top of the head 28 in the position of the latter as shown in Fig. 4. The cylinder 25 also contains a port 29 located below the bottom of the head 27 when the latter is in the position shown in Fig. 4, this port communicating through pipe 32 with any suitable source of fluid-pressure, as for example compressed air.

The bottom opening of the coupling 31 is connected with a stem 33 mounted in, and extending upwardly from, a base 34 at which the mechanism now being described is adapted to be supported. The upper end of the coupling 31 has connected therewith a pipe 35 containing a hand-operated valve 36, the upper end of the pipe 35 opening into the bottom of a cylinder 37 extending upwardly and containing a piston 38 provided with a stem 39 working through an opening 40 in the top of the cylinder 37.

The stem 39 is provided at its upper end with a weight 41, and below this weight with a cross piece 42 held in place thereon by nuts 43, this cross-piece 42 being connected with the upper ends of vertically extending rods 44 spaced apart and located at opposite sides of the cylinder 37. The lower ends of the rods 44 are connected with a disk 45 which surrounds the cylinder 37 and is slideable up and down thereon, this disk containing an opening through which an upwardly extending rod 46 connected with the valve device formed of the stem portion 26 and heads 27 and 28, slidably extends. The rod 46 is provided beneath the disk 45 with a shoulder portion 47, in the form of a nut, and at its upper end is equipped with a tappet 48, a coiled spring 49 surrounding the rod 46 and resting upon the disk 45 for the purpose hereinafter described.

The disk 45 is provided with an upwardly extending spring arm 50 and a downwardly extending spring arm 51, which are secured, as by screws 52 and 53, to brackets 54 and 55, respectively, carried by the disk 45, to extend at their ends represented at 56 and 57, and preferably presenting the converging surfaces as shown, into engagement with the outer surface of the cylinder 37 along which they move in the movement of the disk 45, as hereinafter described. The brackets 54 and 55 are provided with adjusting screws 58 and 59 which bear against the springs 50 and 51, respectively, serving to place them under tension. The springs 56 and 57 coöperate with means, located adjacent the ends of the strokes of the disk 45, for presenting an overcomable resistance to the movement of the disk 45 and the parts connected therewith, these means in the arrangement shown being, at the upper end of the cylinder, presented by the downwardly extending flanged portion 60 of the cylinder cap forming the upper end of the cylinder, and at the lower end of the cylinder being formed of a boss 61 on the wall of the cylinder, the portions 60 and 61 being so located that they will be engaged by the respective spring arms 50 and 51 before the disk 45 reaches the ends of its strokes, and in the final movement of the disk these arms will move beyond the parts 60 and 61.

The valve 24 comprises a casing 62 secured upon the upper end of a pipe 63 which opens into the pipe 23, through the coupling 64. The casing 62 contains a port 65 surrounded by a seat 66 with which coöperates a valve proper 67 having the stem portion 68 which slides in bearings 69 and 70 in the casing 62, this valve closing in an upward direction and preferably having a weighted part 71.

The operation of the apparatus is as follows: Assuming the apparatus to be in the condition represented in Figs. 1 to 5, inclu-

sive, of the drawings, compressed air passes through the pipe 32, port 29 of the valve casing 25 thence through the port 30 and pipe 23 into the upper end of the cylinder 7 wherein it operates to force the water in the cylinder 7, which entered the latter through the inlet 11 in the previous operation of the apparatus, upwardly through the pipe 17 to the point of discharge, the valve 15 being closed and the valve 19 automatically lifting in this operation. During the flow of air to the cylinder 7 as stated, compressed air from the pipe 32 also passes upwardly into the bottom of the cylinder 37, the valve 36 being in open condition, wherein it operates against the underside of the piston 38 forcing the latter and the parts carried thereby, including the disk 45 and the parts connecting the latter with piston 38, upwardly. As the parts just described near the end of their upward stroke, the spring 49 engages the tappet 48 and the spring arm 56, the projection 60, the upward movement of these movable parts being thereby temporarily arrested by the resistance afforded between the spring arm 50 and the projection 60, until the pressure against the bottom of the piston 38 overcomes this resistance, whereupon the arm 50 swings outwardly out of engagement with the portion 60 thus causing the piston 38 and the parts connected therewith to be rapidly impelled upwardly, the valve comprising the heads 27 and 28 in this movement being shifted through the engagement of the spring 49 with the tappet 48, to the position shown in Fig. 6 in which the head 28 extends wholly above the port 30 and a disk 72 secured to the lower end of the stem 26 moves against the bottom edge of the cylinder 25, which is pressed as indicated at 73. The movement of the valve to the position as stated opens the interior of the cylinder 7 and the cylinder 37 to the atmosphere through the port 30, valve casing 25 and port 73 therein, permitting the air from these cylinders to vent, whereupon the pressure of water in the well and surrounding the cylinder 7, forces the valve 15 upwardly and the cylinder 7 becomes charged with water to be expelled therefrom in the next operation of the apparatus. As the piston 38 nears the limit of its downward movement, the spring arm 51 engages the projection 61 operating to produce the overcomable resistance as explained in the upward movement of the piston which is overcome by the weight of the piston and the parts suspended therefrom, after a short pause in the downward movement of the piston and until the air pressure below the piston drops to a degree where it is overcome by the weight of the parts stated, the piston 38 in its final downward movement forcing the valve comprising the heads 27 and 28 to close.

and 28, by the engagement of the disk 45 with the shoulder 47 of the stem 46, to the position shown in Fig. 4, whereupon compressed air again enters the top of the cylinder 7 to force therefrom the water in this cylinder as hereinbefore explained, it being understood that the parts are so proportioned and arranged, by preference, that the valve formed of the heads 27 and 28 is moved to a position in which air enters the cylinder 7 through the pipe 23 immediately upon the cylinder 7 becoming charged with water, and this valve moves to the position shown in Fig. 6 immediately upon the completion of the water-lifting operation.

The valve device 24 is provided for the purpose of aiding in the venting of the cylinder 7, following the operation of forcing the water out of the cylinder 7. The weight of the movable parts of this valve would be such that as soon as the pressure in the pipe 23, between the casing 25 and the cylinder 7, drops by reason of the movement of the valve to the position shown in Fig. 6, it will automatically open and aid in the venting of this portion of the pipe 23, but will quickly close as soon as the valve formed of the heads 27 and 28, moves to the position shown in Fig. 4, to prevent escape of air from the pipe 23 in the water-lifting operation. The prime purpose of the valve 24 is to overcome the necessity of making the pipe 23 of large internal diameter to overcome the resistance to the flow of air-pressure therethrough, as would be necessary where the pipe 23 is provided of a long length.

The valve 36 serves as a means of regulating the flow of air-pressure into the cylinder 37 which is desirable where under conditions of use the degree of back-pressure exerted by the fluid being lifted, varies.

While I have illustrated and described a particular construction embodying my invention, I do not wish to be understood as intending to limit it thereto as the same may be variously modified and altered without departing from the spirit of my invention.

What I claim as new and desire to secure by Letters Patent is:

1. In apparatus of the character set forth, the combination of a cylinder into which the fluid to be lifted enters, and means for alternately introducing fluid-pressure into said cylinder to force the fluid therefrom, and venting said cylinder of the contained fluid-pressure following the fluid-lifting operation comprising a second cylinder, a pipe leading from a source of fluid pressure and communicating with said first-named cylinder, said second cylinder opening into said pipe, a piston in said second cylinder, a member connected with, and movable by, said piston, a valve casing interposed in said pipe and containing ports arranged at

different positions along said casing and in communication with the adjacent portions of said pipe, and a valve proper slidably in said valve casing lengthwise of the latter and formed with heads spaced apart adapted when in one position of the valve to permit of passage of fluid pressure through the pipe into said cylinders and in another position of the valve to shut off the supply of fluid-pressure to said cylinders and vent the latter to the atmosphere, said valve proper being provided with shoulder portions extending in spaced relation lengthwise of the valve and adapted to be alternately engaged by said member for reciprocating said valve.

2. In apparatus of the character set forth, the combination of a cylinder into which the fluid to be lifted enters, and means for alternately introducing fluid-pressure into said cylinder to force the fluid therefrom, and venting said cylinder of the contained fluid-pressure following the fluid-lifting operation comprising a longitudinally movable valve-device, a piston and cylinder device operating said valve device, and means cooperating with the movable element of said piston and cylinder device for presenting to the movement of the latter an overcomable resistance near the end of its stroke only.

3. In apparatus of the character set forth, the combination of a cylinder into which the fluid to be lifted enters, and means for alternately introducing fluid-pressure into said cylinder to force the fluid therefrom, and venting said cylinder of the contained fluid-pressure following the fluid-lifting operation comprising a longitudinally movable valve-device, a piston and cylinder device operating said valve device, and means cooperating with the movable element of said piston and cylinder device for presenting to the movement of the latter an overcomable resistance near the end of its stroke only.

4. In apparatus of the character set forth, the combination of a cylinder into which the fluid to be lifted enters, and means for alternately introducing fluid-pressure into said cylinder to force the fluid therefrom, and venting said cylinder of the contained fluid-pressure following the fluid-lifting operation comprising a longitudinally movable valve-device, a piston and cylinder device operating said valve device, and spring means cooperating with the movable element of said piston and cylinder device for presenting to the movement of the latter an overcomable resistance near the end of its stroke only.

5. In apparatus of the character set forth, the combination of a cylinder into which the fluid to be lifted enters, and means for alternately introducing fluid-pressure into said

- 4
- cylinder to force the fluid therefrom, and venting said cylinder of the contained fluid-pressure following the fluid-lifting operation comprising a longitudinally movable 5 valve-device, a piston and cylinder device operating said valve device, and a spring device movable with the movable element of said piston and cylinder device and bearing against the stationary element of the 10 latter, said stationary element having a projection which extends into the path of movement of said spring-device and operates to temporarily arrest movement of said movable element.
- 15 6. In apparatus of the character set forth, the combination of a cylinder located in the liquid to be elevated and containing an inlet through which the liquid enters the cylinder, an inwardly opening check valve in 20 said inlet, a pipe leading from the upper end of said cylinder and through which the liquid lifted therein is discharged, a second pipe opening into the upper end of said cylinder, a second cylinder communicating with 25 said second pipe, a third pipe leading from the source of fluid pressure, a valve casing communicating with said second and third pipes, a longitudinally movable valve in said valve casing and provided with heads spaced 30 apart adapted when in one position to open said second pipe to said third pipe for supplying fluid pressure to said cylinders and when in another position closing these pipes to each other and venting said second pipe, a 35 piston movable in said second cylinder and carrying a weighted frame, a rod connected with said valve device and extending slid- 40 ingly through said frame, said rod being provided with shoulder portions arranged in spaced relation to said rod and adapted to be alternately engaged by said frame for shifting said valve device, projections on 45 said second cylinder, and spring arms carried by said frame and adapted in the movement of said piston in opposite directions to engage said projections and present over- 50 comable resistance to the movement of said piston.
7. In apparatus of the character set forth, 55 the combination of a cylinder into which the fluid to be lifted enters, and means for alternately introducing fluid pressure into said cylinder to force the fluid therefrom, and venting said cylinder of the contained fluid pressure following the fluid-lifting operation comprising a second cylinder, a piston therein, means for actuating said piston, a frame supported on said piston, a valve casing interposed between said second cylinder and the source of fluid pressure, and a 60 valve in said casing and movable lengthwise therein, said casing and valve extending substantially parallel with said second cylinder, said valve being actuated at its stem directly 65 from said frame and operating when in one position to permit of the flow of fluid pressure to said first-referred-to cylinder and when in another position to interrupt such flow and open said last-referred-to cylinder to the atmosphere. 70
8. In apparatus of the character set forth, the combination of a cylinder into which the fluid to be lifted enters, and means for alternately introducing fluid pressure into said cylinder to force the fluid therefrom, and venting said cylinder of the contained fluid-pressure following the fluid-lifting operation comprising a second cylinder, a pipe leading from a source of fluid pressure and communicating with said first-named cylinder, said second cylinder opening into said pipe, a piston in said second cylinder, a member connected with, and movable by, said piston, a valve casing interposed in said pipe and containing ports arranged at different positions along said casing and in communication with the adjacent portions of said pipe, a valve proper shutable in said valve casing lengthwise of the latter and formed with heads spaced apart adapted when in one position of the valve to permit of passage of fluid pressure through the pipe into said cylinders and in another position of the valve to shut off the supply of fluid pressure to said cylinders and vent the latter to the atmosphere, said valve proper being provided with shoulder portions extending in spaced relation lengthwise of the valve and adapted to be alternately engaged by said member for reciprocating said valve, and a spring interposed between one of said stops and said member. 85
9. In apparatus of the character set forth, the combination of a cylinder into which the fluid to be lifted enters, and means for alternately introducing fluid-pressure into said cylinder to force the fluid therefrom, and venting said cylinder of the contained fluid pressure following the fluid-lifting operation comprising a longitudinally movable valve-device, a piston and cylinder device operating said valve device, a spring device movable with the movable element of said piston and cylinder device, the stationary element of said piston and cylinder mechanism having a projection which extends into the path of movement of said spring-device and operates to temporarily arrest movement of said movable element, and a spring operating to become tensioned while said movable element is temporarily arrested by said projection, and operating, when said movable element passes said projection, to quickly operate said valve device. 100
10. In apparatus of the character set forth, the combination of a cylinder located in the liquid to be elevated and containing an inlet through which the liquid enters the cylinder, an inwardly opening check valve in said inlet, a pipe leading from the up- 105

- per end of said cylinder and through which the liquid lifted therein is discharged, a second pipe opening into the upper end of said cylinder, a second cylinder communicating with said second pipe, a third pipe leading from the source of fluid-pressure, a valve casing communicating with said second and third pipes, a longitudinally movable valve in said valve casing and provided with heads spaced apart adapted when in one position to open said second pipe to said third pipe for supplying fluid-pressure to said cylinders and when in another position closing these pipes to each other and venting said second pipe, a piston movable in said second cylinder and carrying a weighted frame, a rod connected with said valve device and extending slidably through said frame, said rod being provided with shoulder portions arranged in spaced relation on said rod and adapted to be alternately engaged by said frame for shifting said valve device, projections on said second cylinder, spring arms carried by said frame and adapted in the movement of said piston in opposite directions to engage said projections and present overcomable resistance to the movement of said piston, and a spring surrounding said rod and interposed between said frame and the one of said stops on said rod above said frame and operating to become compressed when the upper one of said spring arms becomes engaged with the projection with which it cooperates.
11. In apparatus of the character set forth, the combination of a cylinder into which the fluid to be lifted enters, and means for alternately introducing fluid-pressure into said cylinder to force the fluid therefrom, and venting said cylinder of the contained fluid-pressure following the fluid-lifting operation comprising a longitudinally movable valve device, a piston and cylinder device operating said valve device, a spring device movable with the movable element of said piston and cylinder device, a stationary projection which extends into the path of movement of the said spring device and operates to temporarily arrest movement of said movable element, and a spring movable with the movable element of said piston and cylinder device and through the medium of which said valve device is operated.
12. The combination of piston and cylinder mechanism, a source of fluid-pressure in communication with the cylinder and operating the movable element of said piston and cylinder mechanism, a controlling device controlling the flow of fluid-pressure to the cylinder, stationary projections spaced apart lengthwise of the piston and cylinder mechanism, and spring devices movable with the movable element of said piston and cylinder mechanism and adapted to engage said projections, respectively, said spring means in engaging said projections operating to present to the movement of the movable element of said piston and cylinder mechanism an overcomable resistance in the movement of said movable element in opposite directions.

FRED V. WILLIS.
